WALTER S. DUWELIUS, OF CINCINNATI, OHIO.

DEVICE FOR APPLYING PRESSURE.

1,169,533.

Specification of Letters Patent. Patented Jan. 25, 1916.

Continuation of application Serial No. 39,511, filed July 12, 1915. This application filed August 30, 1915. Serial No. 48,055.

To all whom it may concern:

Be it known that I, WALTER S. DUWELIUS, a citizen of the United States, residing at Cincinnati, county of Hamilton, and State 5 of Ohio, have invented certain new and useful improvements in Devices for Applying Pressure; and I do hereby declare the following to be a full, clear, and exact description of the invention, such as will enable 10 others skilled in the art to which it appertains to make and use the same.

This invention relates to devices for applying pressure and is particularly adapted for use in quoins for use in locking forms 15 of type in chases.

The features of the invention are of special utility in quoins of the type illustrated in United States Letters Patent No. 1,149,037, granted to me August 3rd, 1915.

20 A quoin constructed in accordance with the present invention consists of a hollow metallic casing of rectangular cross-section slotted lengthwise thereof along one face, a plurality of contacting devices within the 25 casing, and means for moving the contacting devices lengthwise of the casing, the devices being so constructed that when they are so moved certain of them are projected more or less through the slotted opening in the 30 side of the casing.

In accordance with the present invention, the members which are projected through the slots in the casing are in the form of blocks having parallel front and rear faces 35 extending lengthwise of the casing and rounded ends, which ends co-act with rollers lying within the casing. Preferably these curved ends of the blocks are formed on radii which constantly decrease in length as 40 the curve approaches the rear face of the block. By reason of this construction, as the extent of projection of the blocks from the casing increases, the leverage of the parts operating to move the blocks outwardly increases. This permits of exerting an increased pressure at the point in the outward movement of the blocks when such increased pressure is most desired.

45 The blocks which are adapted to be projected through the opening in the casing have flanges at their sides adjacent to their rear faces which flanges are adapted to engage walls adjacent to the slot in the casing to prevent the blocks from escaping from the 55 casing. When in their retracted positions,

the blocks have their front faces flush with the face of the rectangular casing. The blocks are supported in these positions upon a thin metallic strip which is inserted within the casing between the rear faces of the 60 blocks and the opposite wall of the casing. This strip supports the blocks in the proper positions and facilitates the ready assemblage of the parts by first inserting the blocks, rollers and spacers within the casing 65 and then inserting the strip behind them.

These and other features of the invention will be better understood by reference to the following description taken in connection with the accompanying drawing, which 70 shows the preferred embodiment of the invention.

In the drawing, Figure 1 is a longitudinal section of my improved form of quoin; Fig. 2 is a top view of the same broken away and sectioned in part; Fig. 3 is a side elevation showing the blocks projected; Fig. 4 is a sectional elevation of a modified form of quoin; and Figs. 5 and 6 are transverse sections showing one of the blocks in its retracted and in its projected positions.

Referring to these drawings, the quoin consists of a tubular frame or casing 7 of rectangular cross-section. On one side this tubular casing is cut away to provide a plurality of slots 8, three such slots being shown in the form of quoin illustrated in Figs. 1, 2 and 3. Each of these slots is of a length somewhat greater than the length of the corresponding block and of a width slightly 90 less than the width of the interior of the casing; in this way flanges are provided at the sides of the slots by the inwardly extending portions of the top wall of the casing.

Within the casing are a plurality of blocks 95 9, one for each of the slots 8. Each of these blocks is of substantially trapezoidal form in that it has parallel front and rear faces extending lengthwise of the casing and ends formed on curves which approximate lines 100 inclined to the front and rear faces. The formation of the curved ends of the blocks is of importance. Preferably each end of each block is curved and the curve is formed on radii which constantly decrease in length 105 from the front to the rear of the block. The result is that the rear portion of the block is curved on a relatively short radius which serves to increase the leverage obtained in moving the block outwardly after the block 110

has been projected a substantial distance. Each of the blocks 9 has flanges 10 extending along its sides adjacent to the rear face as shown in Fig. 5. When a block is projected the maximum distance as shown in Figs. 3 and 6, these flanges 10 engage the lips 11 at the sides of the slot in the casing, so as to prevent further outward movement of a block which would involve escape of 10 the block from the casing.

On each side of each of the blocks 9 are rollers 12 within the casing 7. These rollers are of cylindrical form and of a length equal to the length of the opening within 15 the casing. They are, therefore, retained within the casing at all times, and they contact with the curved ends of the blocks 9. In addition to the blocks 9 and rollers 12, I employ spacers 13 within the casing 7, 20 each spacer being located within the portion of the casing lying between two of the slots 8.

A sheet metal strip 14 of a thickness approximately equal to the thickness of the 25 material employed for the casing 7, is inserted within the casing behind the blocks 9, rollers 12 and spacers 13, that is, between the rear faces of those parts and the adjacent wall of the casing. This strip holds 30 the several blocks 9 normally with their front faces flush with the front face of the casing, as is shown in Figs. 1, 4 and 5, so that at the start of the outward movement of the blocks 9 pressure is applied to the adjacent parts with which the quoin is employed.

The blocks 9 are moved lengthwise of the 40 casing in order to cause them to be projected more or less through the slots in the casing by means of a screw 15 operable from outside the casing. In Figs. 1, 2 and 3, a single screw is shown at one end only of the casing; in a quoin of substantial length I prefer to employ screws at both ends. The 45 threaded shank 16 of the screw passes through a threaded opening in a plug 17 which is secured within the end of the casing 7 and its reduced threaded end enters a threaded opening in a block 18 of rectangular cross-section movable within the opening in the casing 7. The plug 17 is secured within the end of the casing 7 by forming depressions in the plug and forcing the metal of the casing into these depressions. 50 One of the depressions is indicated at 19 in Fig. 2, the depressions being preferably located at the four edges of the rectangular block. In Figs. 3 and 4 where the end of the quoin is shown in elevation, the metal 55 of the casing is shown at 20 as having been forced into the depression 19 in the block 17.

Instead of employing one or two screws located at the ends of the casing as the means for effecting the lengthwise movement of the blocks, I may employ a screw 60

lying within the portion of the casing intermediate its ends and operable from outside the casing through a slot provided therein. Such a construction is shown in Fig. 4 wherein a member having its ends 21 and 22 reversely threaded is located within the casing 7. The central portion 23 of this member is accessible through a cut-away portion of the casing 7 and is provided with holes adapted to be engaged by a suitable tool to 70 turn the member. The threaded ends 21 and 22 enter threaded openings in blocks 24 which are movable lengthwise within the casing 7 and which by their movement force the rollers 12 into engagement with the blocks 9 so as to project the latter through the slots 8 80 in the casing 7.

The quoin thus constructed is adapted to be inserted in a chase with a form of type and the usual furniture, and the screw 15 85 or 23 is then turned so as to cause lengthwise movement of the blocks 9, rollers 12 and spacers 13 within the casing. As the rollers 12 are pressed in the direction of the length of the casing into engagement with the ends of the blocks 9, they tend to force the blocks 9 in a direction at right angles to the length of the casing to project their ends through the slots 8. As the outward movement of the blocks 9 increases, the force 90 tending to move the blocks outward increases by reason of the diminished radius of the curvature of the ends of the blocks near the rear faces of the blocks. This facilitates exerting higher pressure at a time 95 when it is needed most, that is, near the conclusion of the outward movement of the blocks 9. Furthermore, the several blocks 9 will move more or less as may be required to equalize the pressure exerted at different 100 points along the length of the quoin, and if necessary because of inequalities in the chase or furniture, the several blocks 9 will move unequally so as to compensate for such 105 inequalities.

What I claim is:

1. A device for applying pressure comprising a hollow frame-member slotted lengthwise thereof, a plurality of contacting devices arranged in line within the frame-member, and means operable from outside the frame-member for moving the contacting devices in the direction of the length of the frame-member, certain of said contacting devices being blocks having parallel front and rear faces extending lengthwise of the frame-member and having their ends curved on radii decreasing in length toward the rear faces of the blocks; substantially as described.

2. A device for applying pressure comprising a hollow casing of rectangular cross-section closed at its ends and provided with a plurality of lengthwise slots in its face, a plurality of blocks in the casing one lo-

- cated at each of the slots and each having parallel front and rear faces extending lengthwise of the casing and the ends of the blocks being so shaped that the blocks are 5 of greater length adjacent to their front faces than adjacent to their rear faces, rollers in the casing engaging the ends of the blocks, spacers movable within the casing and located in the portions thereof lying between said slots, and means operated from 10 outside the casing for applying pressure to the blocks, rollers and spacers in the direction of the length of the casing, substantially as described.
- 15 3. A device for applying pressure, comprising a hollow casing of rectangular cross-section closed at its ends and slotted along its face, the width of the slotted opening being less than the width of the interior of 20 the casing, blocks in the casing each having parallel front and rear faces extending lengthwise of the casing and lengthwise flanges located at opposite sides adjacent to the rear face to prevent escape of the block 25 from the casing, the ends of the blocks being so shaped that the blocks are of greater length adjacent to their front faces than adjacent to their rear faces, rollers in the casing co-acting with the ends of the blocks, and 30 means operated from outside the casing for subjecting the blocks and rollers to pressure in the direction of the length of the casing, substantially as described.
4. A device for applying pressure, comprising a hollow casing of rectangular cross-section closed at its ends and slotted along its face, a plurality of blocks within the casing having parallel front and rear faces and flanged to prevent escape of the blocks from 40 the casing, a strip lying within the casing between the rear faces of the blocks and the wall of the casing, means operated from outside the casing for moving the blocks lengthwise of the casing, and means co-acting with 45 the blocks to project them through the slotted opening in the casing when they are so moved; substantially as described.
5. A device for applying pressure, comprising the combination of a hollow casing 50 of rectangular cross-section closed at its ends and provided with a plurality of lengthwise slots in its face, a plurality of blocks in the casing one located at each of
- the slots and having parallel front and rear faces extending lengthwise of the casing, a strip lying within the casing and adapted to co-act with the rear face of each block to hold the front face of the block flush with the surface of the casing, means operable from outside the casing for moving the blocks in the direction of the length of the casing, and means actuated by such lengthwise movement of the blocks for projecting the blocks through the slots in the casing; substantially as described. 55
6. A device for applying pressure comprising a hollow casing of rectangular cross-section closed at its ends and provided with a plurality of lengthwise slots in its face, each of which slots is of less width than the width of the interior of the casing, a plurality of blocks within the casing each located at one of the slots and each having parallel front and rear faces extending lengthwise of the casing and curved ends, 70 flanges on the sides of the blocks to prevent escape of the blocks from the casing, a strip within the casing extending under all of the blocks, rollers within the casing contacting with the ends of the blocks, spacers within 75 the casing located at the portions thereof lying between said slots, and means for moving the blocks and rollers lengthwise of the casing to cause the blocks to be projected through the slots in the casing; substantially 80 as described. 85
7. A device for applying pressure, comprising a hollow frame-member slotted lengthwise thereof, a plurality of contacting devices arranged in line within the frame-member, and means for moving said contacting devices lengthwise of the frame-member to cause certain of them to be projected through the slotted opening in the frame-member, said means consisting of a reversely 90 threaded screw lying within the frame-member, nuts movable within the frame-member and co-acting with the threads at the ends of the screw, and a portion intermediate the ends of the screw accessible from the exterior of the frame-member for turning the screw to cause movement of the nuts lengthwise of the frame-member; substantially as 95 described. 100

In testimony whereof I affix my signature. 105
WALTER S. DUWELIUS.
